US0D1038563S

(12) **United States Design Patent** (10) **Patent No.:** **US D1,038,563 S**
(45) **Date of Patent:** **** Aug. 6, 2024**

(54) **CLEANING TOOL**

(71) Applicant: **MOERMAN NV**, Meulebeke (BE)

(72) Inventor: **Jordi Demey**, Wielbeke (BE)

(73) Assignee: **MOERMAN NV**, Meulebeke (BE)

(**) Term: **15 Years**

(21) Appl. No.: **29/837,620**

(22) Filed: **May 6, 2022**

(30) **Foreign Application Priority Data**

Nov. 10, 2021 (EM) 008755318-0001

(51) **LOC (14) Cl.** **07-05**

(52) **U.S. Cl.**

USPC **D32/41**

(58) **Field of Classification Search**

USPC D4/118; D7/688; D8/16, 47; D24/146,
D24/147; D32/15, 17, 35, 40, 41, 42, 44,
D32/49

CPC A47L 1/06; A47L 13/11; A47L 13/16

CLAIM

The ornamental design for a cleaning tool, as shown and described.

DESCRIPTION

FIG. 1 is a front perspective view of a cleaning tool;

FIG. 2 is a rear perspective view thereof;

FIG. 3 is a rear view thereof;

FIG. 4 is a front view thereof;

FIG. 5 is a bottom view thereof;

FIG. 6 is a left side view thereof; and,

FIG. 7 is a top view thereof.

1 Claim, 7 Drawing Sheets
